Primary Examiner — Garth Rademaker*Assistant Examiner* — Melanie Pellegrini(74) *Attorney, Agent, or Firm* — Lerner, David, Littenberg, Krumholz & Mentlik, LLP(57) **CLAIM**

The ornamental design for a camera bracelet, as shown and described.

DESCRIPTION

FIG. 1 is a front perspective view of a camera bracelet showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown in the drawings represent portions of the camera bracelet which form no part of the claimed design.
